UNITED STATES PATENT OFFICE.

LILLIE JOHNSON, OF NORTHWOOD, IOWA.

STOCKING-PROTECTOR.

1,147,404.

Specification of Letters Patent. Patented July 20, 1915.

Application filed July 11, 1914. Serial No. 850,443.

To all whom it may concern:

Be it known that I, LILLIE JOHNSON, a citizen of the United States, residing at Northwood, in the county of Worth and State of Iowa, have invented certain new and useful Improvements in Stocking-Protectors, of which the following is a specification, reference being had to the accompanying drawings.

10 My invention relates to a device for protecting the knees of stockings worn by children from wear and dirt.

It is well known by those having care of small children especially when they engage in either indoor or outdoor plays that the knees of their stockings soon become excessively worn or dirty, and the object of my invention is to provide a device which may be readily adjusted so as to fully protect 20 the knee of the stocking and at the same time not incommod the action of the knees and with this end in view my invention consists in the construction and arrangement hereinafter more fully explained.

25 In order that my invention may be clearly understood, I will proceed to describe the same referring by numerals to the accompanying drawing, in which—

Figure 1 is a perspective view of one of 30 my improved protectors as applied to the leg of a child to protect the stocking knee. Fig. 2 is a view of the protector looking toward the inside face. Fig. 3 is a perspective view of the protector looking toward its 35 outer face.

Similar reference numerals indicate like parts in the figures of the drawing.

1 is the knee protector composed of flexible leather or which may be made of any 40 other suitable material, although leather is preferred for the reason that it is not only wear proof, but likewise water proof and for such reason is desirable for use by children playing upon wet grass.

45 2 is a circular band of any suitable elastic material and capable of being extended to encompass and adhere to legs of varying size at a point below the knee joint, and 3 is a strap which may be either elastic or non- 50 elastic secured to the upper end of the protector and furnished at one end with any ordinary buckle 4.

The protector may or may not be lined according to desire and the side edges are slightly gathered or puckered as shown at 5, 55 to produce the desired vertical and transverse curvature adapting it to like lines of the knee.

In connection with the pad or protector, I employ a safety pin designated 6 and illustrated in Fig. 2, which is intended to engage the trousers so as to prevent any shifting of the pad to one side or the other of the knee, this pin being permanently attached to the 60 protector.

I am, of course, aware that it has been common for workmen when required to assume a kneeling position to apply to the knees pads of some kind of thick and soft material to avoid hurts to the knees, but such 70 devices have been merely make shifts and are cumbrous and greatly retard active articulation of the knee joints and would not subserve the purpose of my invention.

It is to be noted that the darts or puckers 75 5 are disposed in the middle of the knee protector so that a portion extends above the uppermost pair of darts and a portion extends below. These puckers cause the material of the protector to take a cup-shaped 80 form so that the middle portion will fit closely over the knee. The upper portion of the protector will therefore fit closely against the leg above the knee, while the lower portion will fit closely against the leg 85 below the knee. The lower portion is strapped or held to the lower leg by means of the elastic strap 2 which will yield sufficiently to permit easy walking movement or permit the lower leg to be flexed with relation to the upper portion of the leg without binding the knee-pad over the knee and without drawing upon the trousers if the knee-pad is attached to the trousers by 90 means of the safety pin.

Having described the construction and desirable purposes of my invention, what I claim as new and desire to secure by Letters Patent is:—

As a new article of manufacture, a stocking protector for children's use, consisting of a body adapted to the contour of the knee, having at its upper end a strap and buckle adapted to surround the leg above the 100

knee at its lower end, a continuous elastic band adapted to surround the leg below the knee, the upper end of the body being provided with a device adapted to pass through 5 the trouser leg and being engageable therewith to prevent lateral displacement of the protector.

In testimony whereof I hereunto affix my signature in the presence of two witnesses.

LILLIE JOHNSON.
